UNITED STATES PATENT OFFICE.

CLARENCE D. PLATT, OF BRIDGEPORT, CONNECTICUT.

DESIGN FOR A CONNECTOR FOR ELECTRIC WIRES.

SPECIFICATION forming part of Design No. 33,054, dated August 7, 1900.

Application filed June 12, 1900. Serial No. 20,080. Term of patent 7 years.

To all whom it may concern:

Be it known that I, CLARENCE D. PLATT, a citizen of the United States of America, residing in Bridgeport, Fairfield county, in the 5 State of Connecticut, have invented and produced a Design for a Connector for Electrical Wires, of which the following is a specification.

My design for a connector for electric wires is illustrated in the accompanying drawings, in which—

Figure 1 is a perspective view of my design. Fig. 2 is a plan view, and Fig. 3 is an inverted plan.

15 My design comprises a body part B, with two downwardly-extending arms D D on opposite sides, these two arms D terminating in

two inwardly-bent flat parts C C, somewhat resembling the palms of two hands held flat and edge to edge. The body part has holes 20 in it, as at b b. The edge-to-edge hand-like parts C C form the characteristic feature of my design.

I claim as my invention—

The design for a connector for electrical 25 wires substantially as shown and described.

In testimony whereof I have signed my name to this specification in the presence of two subscribing witnesses.

CLARENCE D. PLATT.
